UNITED STATES PATENT OFFICE.

MAX KAPLAN, OF NEW YORK, N. Y.

DESIGN FOR AN ARTIFICIAL LEAF FOR MILLINERY AND THE LIKE PURPOSES.

Application filed February 24, 1922. Serial No. 857. Term of patent 3½ years.

To all whom it may concern:

Be it known that I, MAX KAPLAN, citizen of the United States, residing at the city of New York, in the county of Kings and State of New York, have invented a new, original, and ornamental Design for Artificial Leaves for Millinery and the like Purposes, of which the following is a specification, reference being had to the accompanying drawing, forming part thereof, in which—

The figure is a perspective view of an artificial leaf embodying my new design.

Referring to the drawing, in particular to the features that are most prominent, my new design for artificial leaf is seen to comprise the leaf body portion A from which upstand in neat symmetrical arrangement the lobes or leaf sections B.

I claim:

The ornamental design for an artificial leaf for millinery and the like purposes as shown and described.

MAX KAPLAN.
